UNITED STATES PATENT OFFICE.

ADOLF H. SCHAFFERT, OF YOUNGSTOWN, OHIO, ASSIGNEE TO THE GENERAL FIRE-PROOFING COMPANY, OF YOUNGSTOWN, OHIO, A CORPORATION OF OHIO.

PORTABLE CABINET.

1,047,843.

Specification of Letters Patent. Patented Dec. 17, 1912.

Application filed May 13, 1911. Serial No. 626,912.

To all whom it may concern:

Be it known that I, ADOLF H. SCHAFFERT, a resident of Youngstown, in the county of Mahoning and State of Ohio, have invented 5 a new and useful Improvement in Portable Cabinets, of which the following is a full, clear, and exact description, reference being had to the accompanying drawings, forming part of this specification, in which—

10 Figure 1 is a front elevation partly broken away of my improved cabinet; Fig. 2 is an end elevation of the same; Fig. 3 is a vertical cross section on the line III—III of Fig. 1; Fig. 4 is a partial cross section on the line 15 IV—IV of Fig. 3 on a larger scale; Fig. 5 is a cross-section on the line V—V of Fig. 4; Fig. 6 is a plan view of a portion of one of the sections; Fig. 7 shows a portion of Fig. 3 on a larger scale; Fig. 8 is a bottom perspective view of the top; Fig. 9 is an enlarged partial vertical longitudinal section on the line IX—IX of Fig. 3; Fig. 10 is a perspective view of one of the clamping devices; and Fig. 11 is a detail view of a portion 25 of the handle.

My invention relates to portable, sectional, built-up cabinets, which are usually mounted on wheels so as to be rolled into a safe at night, this device being known in the trade 30 as an "omnibus". Heretofore in the manufacture of such cabinets, each one has been especially designed and then built to order. Consequently, such devices have been expensive, each differing from another in 35 structure, and being made to order by hand.

The object of my invention is to provide a structure of this character which is so constructed and arranged that dealers may keep in stock a number of different types of sections, and may select from these sections and build up at the request of the customer any arrangement thereof which is desired, the built-up sections then being clamped together by suitable clamping devices which will hold 45 them in proper alinement on the truck, if such is used, and prevent their shifting about on each other as the omnibus is moved about.

Another object of my invention is to provide clamping means for the sections which 50 will hold them without the use of screws, bolts or rivets; and to provide for such clamping with varying heights to which the omnibus is built up.

A further object is to provide clamping 55 devices of such character that they may also

be carried in stock by the dealer and may be easily and quickly applied or removed while being adaptable to different heights of the cabinet after it is built up; and also providing for taking out one section after building 60 up and replacing it with another section, if the customer so desires.

In carrying out my invention, I build up the cabinet from a series of horizontal sections, each type of which may be kept in 65 stock so that the customer may select any of these standard sections for building up. When these sections have been selected, the omnibus is built up therefrom, giving the series of sections desired; and a top is then 70 preferably placed on them and the sections secured together by clamping devices so as to provide a strong-rigid structure which can be moved about with the truck without danger of displacing or injuring the sections. Each section may be of any desired 75 height, and may contain filing devices of different kinds; and each section may also be made of partial sections, such as half sections, of which two or more are necessary to 80 complete the horizontal area covered by this complete section, which is the same as the area of the other sections. Where these half sections or part sections are used, the top and bottom sections should be continuous to 85 give a stronger structure.

Each complete section is preferably interlocked with the next section above and below it, so as to bring these sections into proper alinement in building them up and tie them 90 together against easy displacement; and they are then clamped together preferably by corner strips which engage the corners of all the sections, and are suitably secured together to bind them in place. These angle 95 bars may be carried in different lengths to fit the different heights of omnibus which can be built up from the several types of sections.

In the drawings I show a truck having end members 2, 2, consisting of flanged plates extending transversely, and front and rear members 3, 3, whose ends terminate short of the ends of the flanged members 2 and are firmly secured thereto, as by riveting, welding, or otherwise. On this truck, which usually carries casters 4, is fitted the base member 5, which in the form shown consists of an inclosing strip bent into rectangular form, and having top and bottom inwardly projecting 100

105

110

flanges 6 and 7. The ends of this bent strip may be butted together and secured by plate 8, which may be either riveted or spot-welded at the joint. The inwardly flanged 5 ends of this base fit against the ends of the angle bars 2-2, thus preventing endwise movement, while the angle bars 3-3 fit against the front and rear flanges of the base, thus preventing forward or backward 10 movement. The tops of the end flanges of this base section are provided with four headed buttons such as shown at 9, and the same is the case with the top of each section. The bottom of each complete section has corresponding slots 10 with enlarged end portions; so that by fitting the enlarged parts of these bottom holes over the heads of the buttons, and then shoving the fitted section rearwardly the smaller portion of the slot 15 will engage with the neck of the button and hold the section into position after the manner of a bayonet lock.

In the form shown, the section 11 next to the bottom section is in the form of a box 25 with an open front, this box being preferably formed by bending sheet metal into U-shape to form the top 12, the back 13 and the bottom 14. The ends of the box are closed by sheets 15, which are flanged at top, 30 back and bottom, and welded to the top, back and bottom of the box section. The open front end of this section is shown as divided up in any desirable manner by vertical strips a, which are shown as of channel form with 35 the legs of the channel projecting backwardly or inwardly. These channels may be secured by projecting their ends through slots in the top and bottom, and splitting and bending them over, or by a bolt extending 40 within the channel and riveted in the top and bottom of the section, or in any other desirable manner. Within the ends of each section I also preferably provide an inner finishing filler, as shown at 16, this 45 filler consisting of a plate or sheet having its edges flanged outwardly, these flanges being hidden when the filler is pushed into place. In this section, which is provided with filing devices 17, which may be slid 50 in and out, the floor is provided with guideways to engage corresponding guides on the filing devices. These guides are shown as consisting of U-shaped channels 18 secured to the floor and extending from front to 55 the back. The filing devices may be of any desirable form, and are provided with suitable guides 19 on the bottom to engage the guideways on the floor of the section.

In the form shown four sections are provided, namely, 11, 20, 21 and 22, in addition to the top section 23 and the bottom section 5. These sections are generally similar except the thin section 21, which is provided with pull-out shelves 24. In this section 65 the floor may be made of separated strips 25

and 26, as shown in Fig. 6, forward and back stops 27 and 28 being provided to limit the rearward and forward movements of the shelves. The shelves 24 may be guided as in the other sections or in any other desirable 70 way. The top section 23 is preferably formed of a single sheet of metal with its edges flanged down to form the ends, front and back, these portions being provided with inwardly projecting flanges 30, of which the 75 end flanges are provided with the bayonet slots.

When the sections have been built up and interlocked by the bayonet joint devices, the top is applied, and the clamping devices are 80 then secured in place. These clamping devices may be of different forms, but should secure the sections together so that in pushing the omnibus about the sections will not be liable to displacement and the strains of 85 pushing or pulling will be taken on the frame of the clamping device.

In the form shown the clamping devices consist of pairs of angle strips 31, as shown in Figs. 2 and 10, one leg of each angle 90 having an inturned bead or rib portion 32, which is adapted to fit around the flanged-in ends of the sections, as shown at 33 in Figs. 5 and 6 for example. These pairs of clamping strips are kept in stock in different lengths to suit the different heights to which the sections kept in stock may be built up. They are preferably secured together by clamping rods 34 extending through apertured brackets or lugs 35 secured to the strips and held by ornamental nuts 36 on their screw-threaded ends. On these rods I also provide a sliding movable spacer or spacers 37 having flat inner ends 105 preferably faced with cloth or soft material which will not mar the end of the section. Any desirable number of these clamping rods may be used with one or more spacers. The spacers may be swung into position with the inner end engaging the section end, these 110 spacers serving to prevent the rods from moving inwardly against the sections, and also preventing such leverage on the angle strips as would cause them to swing out and disengage as they are pulled together.

In order to provide handles by which the omnibus may be moved about on the casters, I preferably fasten brackets 38 on each of the angle strips, these brackets being provided with a through-rod 39, having end nuts and a surrounding spacing sleeve 40, as shown in Figs. 10 and 11. The spacing sleeve preferably engages circular recesses in the brackets, and is held by drawing the nuts 41 to place. This handle not only serves as a means for moving the omnibus about, but also strengthens the structure.

The advantages of my invention will be apparent to those skilled in the art, since not only is the structure cheapened in cost 130

and made stronger and more convenient, but a customer can be supplied at once with any desired sections in stock forming an omnibus containing any desired filing devices in stock; where heretofore long delay was incurred through the special designing and special hand manufacture thereof. It will be noted that the clamping mechanism engages the sections without marring or disfiguring them, so that even after the apparatus has been put together the sections may be taken out and replaced without having injured or marred them. The main feature of my invention lies in the clamping of the built-up sections together, to give a strong structure which may be moved about as desired.

Within the scope of my invention many changes may be made in the form and arrangement of the sections, the manner of building up and interlocking them, and also in the clamping devices for holding the sections together without departing from my invention.

25. I claim:—

1. A cabinet of the character described, composed of a plurality of separate horizontal sections placed one above another, and vertically extending clamping members 30 engaging the vertical corners of the sections and holding them in proper positions, said clamping members being of angular form to embrace the corners of the sections and one leg of each angle having an inturned 35 bead or lip portion to fit around the inwardly flanged ends of the sections, substantially as described.

2. A cabinet of the character described, composed of a plurality of separate horizontal sections placed one upon the other, and vertically extending clamping members engaging the vertical corners of the sections and holding them in their proper positions, 40 said clamping members being arranged in pairs, one pair at each end of the structure, and the members of each pair being con-

nected by tie members, said tie members having movable spacers bearing against the ends of the adjacent sections, substantially as described.

50 3. A cabinet of the character set forth, comprising a plurality of separable sections or units, clamping members engaging the sections or units and bridging the joints between them, a device connected to the 55 clamping members and constituting a compression member, and a separate contractile tie device connecting the clamping members for drawing them toward each other, said compression member acting as a fulcrum for the clamping members, substantially as described.

4. A cabinet of the character set forth, comprising a plurality of separable sections or units, clamping members engaging the 65 sections or units and bridging the joints between them, a handle bar having its ends connected to the clamping members and spaced from the sections or units, and an adjustable tie rod connecting the clamping 70 members, for drawing them toward each other, substantially as described.

5. A cabinet of the character set forth, comprising a plurality of separable sections or units, angular clamping members detachably 75 engaging the upright corners of the sections or units and bridging the joints between them, a handle bar having its ends connected to the clamping members and being spaced from the sections or units, and a 80 plurality of adjustable tie devices connecting the clamping members, for drawing them toward each other, said devices being disposed closer to the sections or units than the clamping members, substantially as described.

In testimony whereof, I have hereunto set my hand.

ADOLF H. SCHAFFERT.
